UNITED STATES PATENT OFFICE.

JOSEPH V. IRENIUS, OF NEWARK, NEW JERSEY, ASSIGNOR TO IMPERIAL STOPPER COMPANY, A CORPORATION OF MAINE.

BOTTLING APPLIANCE.

1,079,053.

Specification of Letters Patent. Patented Nov. 18, 1913.

Application filed November 22, 1911. Serial No. 661,651.

To all whom it may concern:

Be it known that I, JOSEPH V. IRENIUS, a citizen of the United States, residing at Newark, in the county of Essex and State 5 of New Jersey, have invented certain new and useful Improvements in Bottling Appliances, of which the following is a full, clear, and exact description.

This invention relates to shifting and 10 feeding mechanisms, and more particularly to bottle handling machinery, and has for one of its objects the provision of a novel means for continuously delivering, for example, bottles to points in a suitable mechanism where said bottles may be subjected to 15 some determined operation, such as capping or sealing, and thereafter delivering the bottles or receptacles to convenient points at which they may, if desired, be collected.

20 To attain the ends above mentioned, my herein described invention contains elements and combinations of elements, all of which will be hereinafter referred to and more particularly set forth in the appended claims.

25 Referring to the drawings which form a part hereof and in which like reference characters designate like parts throughout the several views: Figure 1 is a front elevation of one form of bottling apparatus with 30 my novel feeding mechanism applied thereto. Fig. 2 is a section of said apparatus taken on the line II—II of Fig. 1, the front of the apparatus being at the top of the sheet. Fig. 3 is a somewhat diagrammatic 35 detail section taken on the line III—III of Fig. 1, showing the relative positions of the quadrant gears and rack with respect to the plungers. Fig. 4 is a fragmentary detail section taken vertically through the quadrant; the plane of the section being perpendicular to the rack. Fig. 5 is a detail showing the bottle centering means in position 40 upon a plunger. Fig. 6 is a detail elevation of a right hand cam plate which constitutes 45 one element of said means. Fig. 7 is a rear elevation of a similar, but left hand cam plate. Fig. 8 is a front elevation of a knuckle bracket which constitutes another element of said bottle centering means. Fig. 9 50 is a detail showing in plan the bottle centering means and shifting quadrant.

The feeding mechanism has been exemplified in connection with a capping machine. The construction employed in this machine

may of course be varied within wide limits, 55 but the feeding mechanism is particularly well adapted to multiple head machines of the type in question, or of an analogous description. In brief, therefore, the machine illustrated in Fig. 1 comprises side frames 60 or standards 1, suitably connected together to form a frame. This frame carries a table 2, which preferably constitutes the support for the feeding mechanism hereinafter referred to. The capping heads 3 are mounted upon a cross-head 4, which latter further supports the hoppers 5 from which the stoppers or caps are delivered to the mouths of the respective heads preparatory to capping the bottles delivered thereunder. These 70 heads are preferably arranged in alinement, as shown, and correspondingly alined therebeneath are the receptacle supports or plungers 6, which in this form of the capping machine drive the bottles up into the heads 75 for capping the bottles. The construction of these reciprocable parts will not be further referred to, except to state that they may be provided with some form of compensating mechanism to accommodate bottles of different lengths. The plungers are reciprocated by means of cams 7, four of which are provided, the said cams being mounted upon a cam shaft 8. Said cams are preferably arranged in sets of two; being alternated so that one set of cams is in 80 plunger raising position, while the cams of the other set are so disposed that the plungers actuated thereby are in their lowermost position. In other words, counting 85 from the left, the first and third cams, as viewed in Fig. 1, have their longest radii upwardly directed and cams 2 and 4, counting from the left, have their corresponding radii downwardly directed, the cams thus 90 in effect being staggered which tends to render more regular the action of the mechanism and to relieve it from excessive strains. 95

The cam shaft is driven by means of suitable gearing from a shaft 9 which carries 100 the usual driving pulley 10. Each cam 7 is disposed between a pair of bifurcated arms 11 of a depending guide bracket 12 which is secured to the bottom of the corresponding plunger; the shaft 8 being received between the tines of these bifurcated arms. It is obvious, since alternate cams are 105 angularly spaced apart 180°, that one set of

plungers will always be in position to receive a pair of bottles when the plungers of the other set are disposed in bottle capping position, and vice versa. The left hand 5 extremity of the shaft 8, as viewed in Fig. 1, is reduced and carries a bevel or miter gear 13 which is in engagement with a corresponding gear 14 mounted upon the lower extremity of a side shaft 15.

10 As best shown in Fig. 2, the upper extremity of the shaft 15 carries a bevel gear 16 which is in mesh with two similar gears respectively designated 17 and 18. It may here be noted that the shaft 15 is journaled 15 in a lower bracket 19 and an upper bracket 20, which latter also provides a journal for the shaft 21 which carries the gear 17 above, referred to. Shaft 21 also carries a spur gear 22 which is in mesh with a corresponding gear 23 located immediately thereabove, the latter gear being mounted upon the extremity of a horizontal shaft 24. Shaft 24 carries the driving roll 25 of a pair of belts 26; said belts being disposed one upon either 20 side of the center line of the machine and extending around the said driving roll 25 and a roll 27. The latter is mounted upon a shaft 28, journaled in brackets 29, which are secured upon the front edge of the table 2.

25 The bevel gear 18 is mounted upon the rear extremity of a spindle 30 which is journaled in the bracket 20; the said spindle carrying a crank disk 31 upon its forward extremity. This crank disk is provided with a stud 32 30 which is journaled in the extremity of a link 33, and the throw of this link reciprocates a rack 34 which is secured upon a rack bar 35, the latter being slidably mounted in brackets 36 which depend from the under 35 side of the table. The link 33 is preferably connected to the rack bar 35 through the instrumentality of a block 37 which is made adjustable with respect to the said bar; a stud or shoulder bolt 38, carried by the said 40 block, being journaled in the other extremity of the bar 33.

45 Referring now to Figs. 2 and 3, it will be seen that rack 34 is in mesh with a pair of spur gears 39, mounted upon studs 40 in brackets 41 which are secured to the under side of the table 2; and these gears 40 are respectively in mesh with pinions 42, the latter being fixedly secured to the respective lower extremities of a pair of quadrant 50 spindles . . . These spindles are journaled in bosses 44 provided in the table 2, and each of said spindles carries a quadrant 45 which may be secured thereto by means of a set screw 46, for convenience in adjustment. 55 The upper extremities of the respective quadrant spindles may be journaled in brackets 47, the latter being secured in any suitable manner to the upper side of the table. It is evident that when through the 60 rotation of the disk 31 the rack bar 35 is

reciprocated, an alternating rotary motion will be imparted to the spindles 43 through the gears 39 and 42, and that hence each quadrant 45 will be oscillated to and fro about the axis of its supporting spindle. 70 Quadrant shoes 48 are secured upon the respective quadrants; studs 49 which project upwardly from said quadrants being provided for this purpose. For reasons herein-after to be described these shoes should be 75 made readily removable as shown, and to this end it is merely sufficient to slacken and remove nuts 50 carried by the studs 49 when the said shoes may be lifted out of engagement with their respective quadrants. 80

85 Referring now more particularly to Fig. 2, it will be seen that a forked guide-way is provided upon the table. The V-shaped block or stem 51 is preferably disposed upon the median line of the table. This stem is held fixedly in position by means of a stud 52 which projects upwardly between the two belts 26. The under surface of stem 51 overhangs the belts; preferably just sufficient clearance being provided therebetween to allow free passage of the belts thereunder. The apex of this stem is directed outwardly from the plungers, and the rear ends thereof have pivotally connected thereto, as at 53, yielding guide 90 members or gates 54, the latter being normally urged laterally through the instrumentality of springs 55, and the rear extremity of these yieldingly mounted members normally engaging the respective arms 56 of a U-shaped guide block, broadly designated 57. The yieldingly mounted guides 54, and the legs 56 of the block 57, are preferably arcuately formed to a common radius extending from the axis of the corresponding quadrant. Correspondingly disposed to the inner yielding guides 54 are outer yieldingly mounted guides 58, of substantially similar contour, which also are pivotally mounted upon pins 59, springs 60 95 serving to normally hold these members in their innermost position, their rear extremities being, when so disposed, in engagement with the lateral guide blocks 61. These may, in some instances, also be yieldingly mounted, the axis of rotation in each case being a bolt 62, or the like, which preferably extends through a flange upon each of the said blocks, said flange being also slotted as at 63 for the reception of a 100 bolt 64. When a bolt 64 is slackened, the corresponding guide block 61 is free to be swung outwardly a short distance against the action of a spring 65, which tends to hold it in its innermost position: the slot 105 64 limiting the movement of the said block in either direction. The guide elements 58 and 61 are also preferably arcuate, at least in part, in conformity with the elements 54 and 57 previously described. I may also 110 115 120 125 130

provide guide rails 66 which together with the stem 51 form the Y-shaped passage above referred to. It is desirable that at least a portion of these rails be provided, 5 namely the parts 66' thereof which are adjacent the front edge of the table and which extend in parallelism to each other, since these parts perform a function which will be hereinafter more fully discussed. Owing 10 to the tendency of the belts 26, which move in the direction of the arrows indicated thereupon, to hold the bottles against the stem 51, the diverging portions of the rail 66 are not absolutely necessary; but it is 15 preferable to provide them nevertheless, since they prevent inadvertent displacement of the bottles when being transferred by the belts toward the quadrant feeds, as for example, by being knocked over by an operator of the machine. L-shaped brackets 20 67 and 68 serve to support the guide rails 66 above the respective belts, these brackets being secured to the upper surface of the table 2 upon either side thereof; the belts 25 26 being unimpeded thereby. The flat, table-like upper surfaces of the plungers 6 each carry a bracket 69 secured adjacent one edge thereof; two of these brackets being shown in elevated position in Fig. 1. 30 Figs. 5, 6, 7 and 9, illustrate these brackets in detail together with the oscillatable article-shifting cam-plates 70 pivotally mounted thereon. The function of these plates is a dual one in that they serve not 35 only as supports for the bottle or article-engaging members, but also as movable guides for the bottles or articles. As shown in Figs. 6 and 7, the said plates are apertured or recessed as at 71 for the reception 40 of the article-engaging fingers 72, and the combined action of these members and their supporting plates is believed to be distinctively novel.

The brackets 47 are each preferably disposed in a plane intermediate a pair of plungers 6, and have laterally extending therefrom, on either side thereof, arms 73, each of which is provided with a friction roller 74. These rollers are adapted for engagement with the respective plates, when these plates are being elevated by the plungers upon which they are mounted; each plate having a cam surface 75 (see Figs. 6 and 7) upon which the corresponding roller rides; upward movement of a plunger thereby causing rotary movement of the corresponding plate from the position which it occupies with respect to its supporting bracket, shown in Fig. 6, to one 50 corresponding to that shown in Fig. 7. The plates shown in Figs. 6 and 7 constitute a pair, one right hand and one left; and they are alternately swung toward the front of the machine by the upward movement of 55 the respective plungers; and are driven

back into their rearmost positions, also alternately, by the action of the oscillating quadrant 45 which is substantially intermediate said pair of plates.

The fingers 72 are pivotally connected to 70 the respective plates and are each provided with a small crank 76, the extremity of which is adapted for engagement with a detent 77 carried by the corresponding bracket 69. When, therefore, a plate 70 75 is rocked forwardly by the upward movement of its plunger, the finger 72 is swung out from its aperture in said plate by the engagement of the crank 76 with its detent 77, preferably just at the end of such 80 forward throw.

The plate 70 and its finger are held against accidental displacement, the first with respect to its supporting bracket 69, and the second with respect to said plate, by 85 moderate friction. Hence, after the finger has been driven outwardly with respect to the plate it will remain in such position until it is driven back by a succeeding bottle in the manner hereinafter described; while the plate will remain in its forward position until driven rearwardly by the impingement of a lug 78 thereagainst, one of said lugs extending laterally from each side of each 90 quadrant shoe 48.

Having now described the construction of most of the essential parts of my novel feeding mechanism, the remaining parts of the machine may be described while discussing the operation of said machine as a whole.

The belt sections 26 may properly be regarded as constituting a two part belt, since the principal reason for dividing the same into sections is merely to permit the stem or switching piece 51 to be secured directly to the center of the table. Assuming now that these belt-sections are being driven in the direction indicated by the arrows thereupon; that the plungers are being reciprocated in the manner above described and that the quadrants are being oscillated by the gears, rack, link and disk in an obvious manner. Bottles 79 may now be delivered through the parallel guides 80, being advanced therebetween from, let us say, the filling apparatus 110 in any suitable manner, as by means of a belt 81 passing over an idler 82. The bottles are shoved by belt 81 on to a plate 83, in a well known manner and are driven thereover by succeeding bottles, on to the two-part belt 115 26. It will be observed that the guide parts 66' are spaced apart a distance somewhat greater than the diameter of the bottles 79, so that the slight resistance to their progress offered by the stem 51 which is directly in 120 their path suffices to cause them to stagger with respect to each other. To this end it is desirable that the belt 81 be driven at, at least, as great a speed as the belts 26, and preferably the belt 81 is driven at a some- 125 130

- what higher rate so that even before the bottles encounter the stem, they begin to stagger themselves in the passage between guides 66', in the manner shown in Fig. 2. 5 By reason of this staggering action, the bottles will automatically apportion themselves, usually alternately, toward the respective sides of the machine. The belts 26 tend to hold them against the sides of the stem, 10 along which they slide, until they have entered the respective passage-ways between guides 54 and 58. They are then carried through said passage-ways until, usually, they successively encounter the respective 15 curved faces 84 of the quadrant-shoes 48. These shoes block said passage-ways and only permit the bottles to emerge therefrom at determined intervals. If the quadrants, which preferably swing in unison, are disposed to the right, as shown in Fig. 2, then 20 a single bottle is free to emerge from each of said passage-ways and such bottles will immediately thereafter be swung or shifted to the left, by the rotary action of the quadrants. Usually the belts serve to hold the 25 bottles firmly against the quadrant shoes until they have been swung past the mouths of the passage-ways; but if by any chance, a bottle should not have properly entered 30 the pocket 85 provided upon the side of a quadrant shoe, so that such bottle would be pinched between guide 58 and said shoe, the guide 58 will yield, permitting the bottle to snap one way or the other. Similarly, 35 but much more rarely, if a bottle has so displaced a guide 58 and has lodged against the edge of a guide 61, such guide will in turn yield, and the bottle will be advanced toward the bottling heads without breakage. 40 The belt-sections tend to advance those bottles traversing the inner arcuate paths for a greater distance along said paths than they do those bottles moving over the outer paths and it is probably for this reason that it has 45 been found practically unnecessary to make the guide parts 56 yieldable.
- The bottles shifted by the quadrants are placed thereby directly upon the plungers, a plunger always being in its downmost position when the corresponding quadrant is 50 swung theretoward. It is evident therefore that the quadrants and plungers should move in timed relationship. When a bottle is being pushed onto a plunger, in the manner described, the lug 78 of the quadrant shoe, which forms a part of the wall of the pocket 85 which holds said bottle, engages the corresponding plate 70 and drives it rearwardly. The bottle engaging finger 72 55 of this plate had previously been swung outwardly from said plate when the plate was rocked forwardly, and as the plate now travels toward the rear of the machine, this finger advances the bottle ahead of that be- 60 ing delivered by the quadrant; shoving it off 65 from the plunger onto the table, as shown at the right in Fig. 2.
- The bottles leaving the plungers are driven by succeeding bottles over the surface of the table, between guides 86—87; the latter preferably being fixed and the former being pivotally mounted upon the table as at 88, being adjustable thereover to accommodate bottles of different sizes. It may here be noted that the bottles shown are 70 75 quart bottles. The bottles being positioned on the plungers by the quadrants are centered with respect to the bottling heads by means of centering devices, one of which is carried by each of said plungers. These devices are simple in construction but embody certain novel features, and are especially well adapted to co-act with the feeding mechanism. Each centering device consists of a bracket 89, the base 90 of 80 85 which is doweled upon the corresponding plunger, each base preferably being provided with at least two sets of dowel holes 91, 92; in order to permit of adjustment of said bracket toward and from the axis of 90 the plunger, accommodating different sizes of bottles.
- Brackets 89 are apertured as at 93 in Figs. 8 and 9, for the reception of knuckles 94, the bent or angular portions of which 95 protrude through said apertures; said knuckles being hinged in pairs upon pins 95 in said brackets. The knuckles are spring pressed; leaf springs 96 being secured to the brackets, as at 97 and bearing against the 100 ends of the knuckles; said ends being held thereby normally in engagement with the sides of the brackets.
- When a bottle is driven against an inclined face of a knuckle by the action of a quadrant, said knuckle yields and the bottle slides past the angle thereof into the V-shaped pocket formed by the inner, inclined sides of a pair of knuckles, thus disposing said bottle in substantial alignment with 105 the axis of the capping head. Thereafter the quadrant moves away and the plunger bearing said bottle rises, applying the cap to the bottle in a well known manner. As 110 said plunger rises, the plate 70, carried thereby encounters the roller 74 and the plate is rocked forwardly in the manner above described. The finger 72 of said plate is, at the commencement of this movement, outwardly extended with respect to 115 the plate; but as the plate swings toward the front of the machine, this finger is pushed back out of the way by the bottle which is being capped, and passes to the right of said bottle, as viewed in Fig. 9. 120 At the end of the stroke of the plate 70, this finger is again driven out by its crank 125 engaging the detent 77, the tip of the finger

preferably just clearing the bottle. The next movement of the quadrant, clockwise, as viewed in said Fig. 9, drives plate 70, its finger and the bottle to the left thereof, off 5 from the plunger, as previously described.

The quadrant shoes are made readily removable from the quadrants to accommodate bottles of different sizes; shoes being provided of substantially the shape shown, 10 but of different sizes, for different types of bottles.

While I have described my feeding mechanism in connection with a capping machine, it is to be understood that the term "bottling machine" hereinafter used in the appended claims is to be regarded as of sufficient breadth to include not only capping or sealing machines, but also bottle filling machinery and, in general, bottle handling 20 apparatus of any description.

The mechanism exemplified has been shown as set for bottles of relatively large size. Smaller sizes of bottles may be handled by changing the quadrant shoes; shifting the brackets 89 in the manner described; 25 and adjusting the pivoted guides 86.

The brackets 69 and plate 70 are readily removable and may be substituted by similar brackets and plates adapted for the 30 smaller bottles; while the guides 66, 54, 58, etc., may have shoes superposed thereupon to reduce the widths of the passage-ways therebetween. A fragment of such a shoe is shown at 98 overlying one of the guides 35 66 and secured thereto by dowels 99.

Having described my invention, I claim:

1. In bottling appliances, an apparatus having a plurality of means for performing similar operations upon a plurality of bottles substantially simultaneously, feeding mechanism for shifting bottles, delivered 40 from a common source, into diverse paths, said paths leading toward the respective devices aforesaid, said mechanism comprising a stationary bottle apportioning stem at the juncture of two of said paths and co-acting 45 means for advancing a series of bottles toward said apportioning stem, in combination with means for successively centering 50 bottles, traversing the respective diverse paths, with respect to the devices corresponding to said paths.

2. The combination of a multiple-head bottling appliance with feeding mechanism 55 for shifting bottles toward the respective heads of said appliance, said mechanism comprising an oscillatable bottle switching device, movable in one plane, and a second oscillatable bottle shifting device movable 60 in a second plane, the first of said devices adapted to engage one bottle and the second of said devices adapted to engage another bottle approximately contiguous to that first mentioned.

3. In a feeding mechanism, the combination of a rotatable member adapted to shift articles being fed through said mechanism with means for moving said member, and a plurality of substantially juxtaposed guides, one of which is laterally movable to 70 prevent injury to said articles by the movement of said member, another of said guides constituting a stop to limit movement of said first mentioned guide toward said member.

4. In a feeding mechanism, the combination of a rotatable member adapted to shift articles being fed through said mechanism with means for moving said member, and a plurality of substantially juxtaposed guides, one of which is laterally movable to 75 prevent injury to said articles by the movement of said member, another of said guides constituting a stop to limit movement of said first mentioned guide toward said member, said second guide also being laterally movable under excessive pressure.

5. The combination of a multiple head bottling appliance with feeding mechanism for shifting bottles toward the respective heads of said appliance, said mechanism 90 comprising separate elements each adapted to positively engage successive bottles substantially simultaneously, one of said elements being pivotally mounted, the axis of rotation of one of said elements being substantially at right angles to the respective 95 axes of the heads of said bottling appliance.

6. In bottling appliances, an apparatus having a plurality of means for performing similar operations upon a plurality of bottles substantially simultaneously, each of said means comprising a plunger, feeding mechanism for shifting bottles toward said plungers, yielding centering means carried by plungers, said centering means receiving 105 bottles from said feeding mechanism.

7. In a feeding mechanism, an oscillatable member, a second oscillatable member movable by said first member, said members being movable in different planes, said second 110 member carrying an element pivotally attached thereto, and means for oscillating said pivoted element in accordance with the movements of said second member, said pivoted element being adapted to engage 115 articles to be fed to said mechanism.

8. In a feeding mechanism, a rotatable member, a finger pivotally connected to said member, said finger being movable substantially into alinement with said member, 120 means for rotating said finger out of alinement with said member, said finger when so positioned being adapted for engagement with articles to be fed by said mechanism, and means for actuating said member.

9. In a feeding mechanism, a rotatable member, a finger pivotally connected to said member, said finger being movable substan-

tially into alinement with said member, means for rotating said finger out of alinement with said member, said finger when so positioned being adapted for engagement 5 with articles to be fed by said mechanism.

10. In a feeding mechanism, a support, a movable member having a recess therein, said member mounted on said support, a finger connected to said member and movable into and out of said recess, and means for moving said finger out of said recess when the member is moved in one direction with respect to said support, said finger adapted for engagement with articles to be 15 fed by said mechanism.

11. The combination of a bottling appliance having a plunger, with feeding mechanism for moving bottles into alinement with said plunger, said mechanism comprising an 20 element pivotally mounted upon said plunger and movable therewith, means carried by said element for engaging bottles, and means adapted for engagement with said element for effecting movement thereof in 25 accordance with a movement of said plunger.

12. The combination of a bottling appliance having a plunger, with feeding mechanism for moving bottles into alinement with 30 said plunger, said mechanism comprising an element mounted upon said plunger and also laterally movable with respect thereto, means carried by said element for engaging bottles, and means adapted for engagement 35 with said element for effecting lateral movement thereof in accordance with a movement of said plunger.

13. The combination of a bottling appliance having a plurality of heads, with feeding 40 mechanism for shifting bottles toward the respective heads of said appliance, said mechanism comprising guide members spaced apart a greater distance than the diameter of the bottles to be fed by said mechanism, a belt for advancing said bottles between said guides, and a switching device disposed in the path of said bottles, said device co-acting with said belt and guides to stagger the bottles advancing toward said 50 device, whereby said bottles may be apportioned between at least two of said heads.

14. Feeding mechanism for shifting bottles delivered from a common source, into diverse paths, said mechanism comprising 55 guides spaced apart a distance substantially equal to the diameter of said bottles, a second set of guides spaced apart a distance materially greater than the diameter of said bottles, the median lines between said sets 60 of guides being substantially coincident, a

belt for receiving bottles delivered from said first set of guides, the carrying surface of said belt being beneath said second set of guides, a shifting stem having sides adapted for engagement with said bottles, said sides 65 being angularly disposed with respect to each other, said stem, belt and guides co-acting to stagger bottles passing between said second set of guides and to shift said staggered bottles alternately toward opposite 70 sides of said stem.

15. In bottling appliances, a feeding means for bottles, comprising a channel of greater width than the diameter of the bottles, means for forcing the bottles through 75 said channel, a stationary stem arranged at the end of said channel and two branching channels leading from said first mentioned channel along the respective sides of said stem whereby the bottles which are compelled to pass through said first mentioned channel in staggered relation to each other are successively directed first into one of said branch channels and then into the other by said stationary stem. 80

16. The combination of a bottling appliance having a plurality of heads, with feeding mechanism for shifting bottles toward the respective heads of said appliance, said mechanism comprising guide members 90 spaced apart a greater distance than the diameter of the bottles to be fed by said mechanism and means for pressing the bottles against each other while they are passing between said guides to thereby impart a 95 staggered relation between the bottles, and a switching device disposed in the path of the bottles whereby said bottles are apportioned between at least two of said heads.

17. The combination of a bottling appliance having a plurality of heads, with feeding mechanism for shifting bottles toward the respective heads of said appliance, said mechanism comprising guide members spaced apart a greater distance than the diameter of the bottles to be fed by said mechanism, 100 and means for pressing the bottles against each other while they are passing between said guides to thereby impart a staggered relation between the bottles, and a stationary guide disposed in the path of said bottles whereby said bottles are apportioned between at least two of said heads. 105

In witness whereof, I subscribe my signature, in the presence of two witnesses.

JOSEPH V. IRENIUS.
